UNITED STATES PATENT OFFICE.

HARRY W. LOWE, OF OMAHA, NEBRASKA, ASSIGNOR, BY MESNE ASSIGNMENTS, TO SPRAGUE CANNING MACHINERY CO., A CORPORATION OF ILLINOIS.

FINISHING-MACHINE.

1,393,949.

Specification of Letters Patent.

Patented Oct. 18, 1921.

Application filed March 21, 1917. Serial No. 156,489.

To all whom it may concern:

Be it known that I, HARRY W. LOWE, a citizen of the United States, residing at Omaha, in the county of Douglas and State 5 of Nebraska, have invented new and useful Improvements in Finishing-Machines, of which the following is a full, clear, concise, and exact description, reference being had to the accompanying drawing, forming a 10 part of this specification.

My invention relates to finishing machines and more specifically to finishing machines for catsup.

One of the objects of my invention is 15 to provide an improved finishing machine for catsup, or the like, which will not force foreign substances, such as mold and the undesirable parts of the tomatoes such as the harder green portions, through 20 the screen, thereby insuring a smooth uniform high grade product. Further objects will appear from the detail description to follow and from the appended claims.

In the drawings in which one embodiment 25 of my invention is shown:

Figure 1 is a vertical axial section through a finishing machine embodying my invention.

Fig. 2 is an end elevation of the machine 30 viewed from the left of Fig. 1.

Fig. 3 is a plan view of the machine.

Fig. 4 is a detail sectional view showing the location of the brush with respect to the screen.

Fig. 5 is a section on the line 5--5 of 35 Fig. 1.

Fig. 6 is a detail view of the spider which actuates the brushes.

Referring now to the drawings in detail, 40 the finishing machine shown, comprises a perforated frusto conical screen 10 which may be of sheet brass, a nest of brushes, 11, pivotally mounted to operate in said screen, to force the material through the perforations of the screen, means 12 for rotating said brushes, means, 13, for supplying the material to said screen, refuse collecting and discharge means 13^a for disposing of the material which is not forced through the 45 screen by the brushes, a bowl or tank 14 surrounding the screen 10 to receive the material forced through the perforations of the screen and a supporting frame or base 15, on which the various parts are mounted.

The screen 10 is closed at the bottom as 55 indicated at 16 and is provided at its upper end with an annular frame 17 which rests on the ledge 18 of the annular channel member 19. This channel member 19 is provided with oppositely disposed trunnions 20 60 mounted in bearings 21 on the frame 15.

Each of the brushes 11 is hingedly secured at 22 to a brush ring 23. The nest of brushes rest freely and pivotally in the conical screen 10. 65

The means 12 for rotating the brush ring with the nest of brushes, comprises a spider 24, the arms 25 of which engage with hook shaped lugs 26 on the ring 23, a hollow shaft 27, to which the spider 24 is secured, a bevel gear 28 secured on the shaft 27, a bevel pinion 29 meshing with the bevel gear 28, a shaft 30 on which the bevel pinion 29 is secured and a pair of fast and loose pulleys 31 and 32 mounted on the shaft 30. As 70 shown in Fig. 1, the engagement between the arms 25 and the lugs 26 is somewhat loose. This permits the ring 23, and hence the brushes 11 to act as floating members when the arms are rotated, to enable the brushes 75 to adjust themselves to the screen 10, this adjustment being further facilitated by the pivotal connection at 22, which also acts to allow the brushes to float to adjust themselves to the screen. The shafts 27 and 30 80 are rotatably mounted in bearings 33, 34, 35 in the bearing bracket 36, which is pivotally mounted on the frame 15 by means of a shaft or pin 37. This pivotal mounting of the bracket 36 permits the shafts 27 and 30, 85 with associated mechanism, to be swung up away from the nest of brushes and out of the conical screen 10, to permit access to the brushes and screen for cleaning, etc. 90

The means 13 for supplying the material 95 to the perforated screen, comprise in addition to the hollow shaft 27, a tubular connection 38, threaded into the gear casing 39 and communicating with the hollow shaft 27.

The refuse collecting and discharge means 100 13^a comprise a refuse sweep 40 operating in the channel member 19 and secured to one of the brushes, and a discharge chute 41, leading from a suitable opening 42, formed in the side of the channel member 19. The 105 channel member 19 may be provided with a suitable cover 43. The bowl or tank 14 is provided with oppositely located lugs 44

secured to the frame 15 and with an opening 45 at its lower end for the discharge of the finished product.

The operation of my improved device is as follows: Power is applied to the fast pulley 31 by means of a dog causing the shaft 30 to rotate and with it the metal pinion 29. This causes the rotation of the bevel gear 28, hollow shaft 27, and spider 25, the arms of the spider 25 engage the hook shaped lugs 26, causing the rotation of the brush ring and nest of brushes.

Material such as tomatoes, from the pulping machine is supplied to the screen 10, through the tubular connection 38 and hollow shaft 12. This material flows out between the brush and screen, and the brushes as they revolve, force the material through the perforations in the screen. The brushes are floatably mounted and bear on the pulp with a yielding pressure so as not to force substances such as mold and the undesirable parts of the tomatoes, such as the hard green portion, through the perforations in the screen. The finished material forced through the perforations in the screen 10 escapes into the bowl or tank 14 and is discharged through the opening 45. The foreign substances and the harder portions of the tomatoes are gradually worked upwardly along the sides of the screen 10 due to the action of the brushes, and centrifugal force, and escape into the channel member 19. The refuse sweep 40 operating in the channel member 19 sweeps the refuse along the channel member and out through the opening 42 into the discharge chute 41.

In working along the sides of the screen these foreign substances act somewhat as a pressure mat between the brush and the surface of the screen. In operation, the brush assumes a position such as shown in Fig. 4, the lower part of the brush being farther from the screen than is the upper part of the brush. The result of this operation is that no undesirable substances are forced through the screen and the finished product is of good color and high quality.

When it is desired to have access to the screen 10 or brushes 11, for cleaning purposes, etc., the spider 25 may be rotated slightly to free it from the hook-shaped lugs 26, after which the bracket 36 can be swung about the pin 37 to lift the shaft 27 and spider 25 away from the brushes 11. In doing this, it is, of course, necessary to disconnect the tubular connection 38. The nest of brushes can then be lifted out of the screen and if desired, the screen and the channel member 19 may be lifted out of the same to permit access to the bowl 14.

Having described my invention, what I claim as new and desire to secure by Letters Patent, is:—

1. In a finishing machine, a conical per-

forated screen having a vertical axis, means for supplying material to said screen, and means for forcing the material through said screen, comprising a floatably mounted brush.

2. In a finishing machine, a conical perforated screen having a vertical axis, means for supplying material to said screen, and means for forcing the material through said screen, comprising a plurality of floatably mounted brushes.

3. In a finishing machine, a conical perforated screen having a vertical axis, means for supplying material to said screen, and means for forcing the material through said screen, comprising a plurality of brushes, a floatably mounted member to which said brushes are secured and means for rotating said floatable member.

4. In a finishing machine, a conical perforated screen having a vertical axis, means for supplying material to said screen, and means for forcing the material through said screen, comprising a plurality of brushes, a floatably mounted member to which said brushes are pivotally secured and means for rotating said floatable member.

5. In a finishing machine, a conical perforated screen, means for supplying material to said screen, and means for forcing the material through said screen, comprising a floatably mounted brush, an annular passage above said conical screen and a sweep operating in said annular passage for removing the refuse which enters said passage from said screen.

6. In a finishing machine, a conical perforated screen, means for supplying material to said screen, and means for forcing the material through said screen, comprising a plurality of brushes, a floatably mounted member to which the said brushes are secured and means for rotating said floatable member, an annular passage above said conical screen and a sweep operating in said annular passage for removing the refuse which enters said passage from said screen.

7. In a finishing machine, a conical perforated screen having a vertical axis, means for supplying material to said screen, and means for forcing the material through said screen, comprising a plurality of brushes, a floatably mounted member to which said brushes are secured and means for rotating said floatable member, comprising a shaft co-axial with said screen.

8. In a finishing machine, a conical perforated screen having a vertical axis, means for supplying material to said screen, and means for forcing the material through said screen, comprising a plurality of brushes, a floatably mounted member to which said brushes are secured and means for rotating said floatable member, comprising a shaft co-axial with said screen, said shaft being

- hollow to provide a passage for the material to said screen.
9. In a finishing machine, a conical perforated screen having a vertical axis, means for supplying material to said screen, and means for forcing the material through said screen, comprising a plurality of brushes, a floatably mounted member to which said brushes are secured and means for rotating 10 said annular floatable member.
10. In a finishing machine, a conical perforated screen, means for supplying material to said screen, and means for forcing the material through said screen, comprising 15 a plurality of brushes, a floatably mounted member to which said brushes are secured and means for rotating said annular floatable member, comprising a shaft co-axial with said screen and a spider secured to said 20 shaft for driving said rotatable member.
11. In a finishing machine, a conical perforated screen, means for supplying material to said screen, and means for forcing the material through said screen, comprising 25 a plurality of brushes, a floatably mounted member to which said brushes are secured and means for rotating said floatable member, comprising a shaft co-axial with said screen, and a swinging bracket in which 30 said shaft has a bearing whereby said shaft may be swung out of said screen.
12. In a finishing machine, a conical perforated screen, means for supplying material to said screen, and means for forcing the material through said screen, comprising 35 a plurality of brushes, a floatably mounted member to which said brushes are secured and means for rotating said floatable member, comprising a shaft co-axial 40 with said screen, and a swinging bracket in which said shaft has a bearing, said shaft having a separable connection with said brushes, whereby said shaft may be swung out of said screen, leaving the brushes in 45 place.
13. In a finishing machine, a conical perforated screen having a substantially vertical axis and tapering downwardly, means for supplying material to said screen, a member rotatable about the axis of said screen, and a brush pivotally mounted for movement about a substantially horizontal axis with respect to said rotatable member, for forcing the material through said screen.
- 50 14. In a finishing machine, a conical perforated screen having its axis substantially vertical and tapering downwardly, an annular member concentric with respect to said screen and rotatable about the axis thereof, a series of brushes pivotally mounted to move about substantially horizontal axes with respect to said annular member, for forcing the material through said screen, and means for supplying material to said 55 screen.
15. In a finishing machine, a conical screen having its axis substantially vertical and tapering downwardly, means for supplying material to said screen, a brush rotatable about said axis for forcing material through said screen and for forcing the refuse upwardly to the upper edge of said screen, a passage adjacent the upper edge of said screen for receiving the refuse from said screen, and a sweep secured to said brush and operating to discharge the material from said passage.
16. In a finishing machine, a conical screen, means for supplying material to said screen, a brush mounted for rotation about the axis of said screen for forcing the material through said screen, a shaft coaxial with said screen and having a detachable connection with respect to said brush, and a swinging bracket in which said shaft has a bearing, whereby said shaft may be disconnected from said brush and swung out of said screen.
17. In a machine of the character described, a screen, a substantially vertical rotatable hollow shaft through which material is supplied to said screen, a brush driven by said shaft for forcing material through said screen, a bevel-gear secured to said hollow shaft for driving it, and a second bevel-gear meshing with said first bevel-gear for driving it.
18. A finishing machine comprising a downwardly tapering conical screen having a vertical axis, a combination supply tube and drive shaft rotatably mounted coaxially with said screen, an inclined brush operating against the inner surface of said screen and secured to said rotatable shaft, said screen being stationary, and a downwardly tapering conical housing and receiving member immediately surrounding said screen, for receiving the material as it is forced through the screen by said brush, said housing having a discharge opening for the discharge of the finished material, and means for discharging the refuse which is forced up over the upper edge of said conical screen.
19. A finishing machine comprising a downwardly tapering conical screen having a vertical axis, a combination supply tube and drive shaft rotatably mounted coaxially with said sleeve, said combination tube and shaft serving to supply material to the screen, an inclined brush operating against the inner surface of said screen, a spider connecting said brush with said rotatable shaft, said screen being stationary, and a downwardly tapering conical housing and receiving member immediately surrounding said screen, for receiving the material as it is forced through the screen by said brush, said housing having a discharge opening for the discharge of the finished material, and means for discharging the refuse which is

forced up over the upper edge of said conical screen.

20. A finishing machine comprising a downwardly tapering conical screen having 5 a vertical axis, a vertical drive shaft coaxial with said screen, an inclined brush operating against the inner surface of said screen and driven from said shaft, and a pivotally mounted bearing bracket in which 10 said shaft is mounted, said bracket being pivoted to swing said shaft out of said conical screen, to permit access to the screen, for cleaning and repairs.

21. A finishing machine comprising a 15 downwardly tapering conical screen having a vertical axis, a combination supply tube and drive shaft coaxial with said screen,

an inclined brush operating against the inner surface of said screen and driven from 20 said shaft, said combination supply tube and drive shaft serving to supply material to said screen, and a pivotally mounted bearing bracket in which said shaft is mounted; 25 said bracket being pivoted to swing said shaft out of conical screen to permit access to the screen for cleaning and repairing.

In witness whereof I have hereunto subscribed my name in the presence of two witnesses.

HARRY W. LOWE.
